UNITED STATES PATENT OFFICE.

WILLIAM TAYLOR, OF PITTSBURG, PENNSYLVANIA, ASSIGNOR TO THE
ANGULAR STEEL NAIL COMPANY, (LIMITED,) OF SAME PLACE.

SPIKE.

SPECIFICATION forming part of Letters Patent No. 278,628, dated May 29, 1883.

Application filed January 19, 1883. (No model.)

To all whom it may concern:

Be it known that I, WILLIAM TAYLOR, a citizen of Great Britain, residing at Pittsburg, in the county of Allegheny and State of Pennsylvania, have invented a new and Improved Spike and Plan of Making the Same, of which the following is a specification.

This invention relates to certain improvements in bolts or spikes for securing the rails in railroads to the sleepers or ties; and it has for its object to provide a spike which, when driven home, will be permanently held in its seat, as more fully hereinafter specified.

The above-mentioned object I attain by the means illustrated in the accompanying drawings, in which—

Figure 1 illustrates a side elevation of my improved spike or bolt; Fig. 2, a longitudinal sectional view of the same; Fig. 3, an elevation of the bolt or spike, and Fig. 4 a cross-section of the same.

The letter A indicates the spike or bolt, which is provided with the usual head, preferably extended to one side, as shown. The said spike or bolt has formed on opposite sides longitudinal recesses B, as indicated. These recesses are formed during the construction of the bolt or spike, and extend from a point near the head to a point commencing at the bevel of the bolt, and within said recesses are formed corrugations or ribs D, which hold and

bind into the wood when the spike or bolt is driven therein. The grooves are curved so that the depth will be greatest midway between the two ends, so as to secure a perfect 35 wedging effect when driven into the wood.

It will be seen that, as thus constructed, when the spike is driven into the sleeper, it will first displace the fibers of the wood, which will afterward spring into the grooves and be 40 held and engaged by the corrugations, causing a perfect dovetail with the spike and preventing its removal under any strain without stripping the wood or breaking the spike.

I am aware that spikes have been heretofore made with straight longitudinal recesses provided with transverse ribs or corrugations, and such I do not intend to claim.

Having thus described my invention, what I claim, and desire to secure by Letters Patent, 50 is—

A railroad-spike having curved corrugated grooves on opposite sides, the said grooves commencing at a point near the head and terminating near the beveled end, and having 55 their greatest depth midway between the ends, substantially as specified.

WILLIAM TAYLOR.
